US00D962603S

(12) United States Design Patent (10) Patent No.: US D962,603 S
(45) Date of Patent: * Sep. 6, 2022

(54) SHOE

- (71) Applicant: PUMA SE, Herzogenaurach (DE)
(72) Inventor: Matthias Hartmann, Forchheim (DE)
(73) Assignee: PUMA SE, Herzogenaurach (DE)
() Term: 15 Years
(21) Appl. No.: 29/730,910
(22) Filed: Apr. 9, 2020

Related U.S. Application Data

- (60) Continuation of application No. 29/709,858, filed on Oct. 17, 2019, now Pat. No. Des. 923,297, which is a division of application No. 29/632,375, filed on Jan. 8, 2018, now Pat. No. Des. 876,052.
